GAME BOARD

Louis Zaris, 1516 Atlantic Ave.,
Atlantic City, N.J. 08401

Filed Jan. 2, 1973, Ser. No. 320,289

Term of patent 14 years

Int. Cl. D21—01

U.S. Cl. D34—5 SS

FIG. 1 is a top plan view showing my design of a game board.

FIG. 2 is a reduced side edge view.

FIG. 3 is a reduced bottom view.

FIG. 4 is an upper edge view of FIG. 3.

FIG. 5 is a lower edge view of FIG. 3.

FIG. 6 is a side edge view showing the side edge opposite that of FIG. 2.

I claim:

The ornamental design for a game board, as shown and described.
